United States Patent Office

Des. 232,677

Patented Sept. 10, 1974

232,677

STORAGE CABINET

Ronald S. Schotland, Honey Brook Drive, R.D. 2,
Princeton, N.J. 08540

Filed Dec. 18, 1972, Ser. No. 316,292

Term of patent 14 years

Int. Cl. D6—04

U.S. Cl. D6—127

FIG. 1

FIG. 2

FIG. 3

FIG. 4

FIG. 1 is a perspective view of a storage cabinet showing my new design;

FIG. 2 is a side elevational view thereof;

FIG. 3 is a rear elevational view thereof;

FIG. 4 is a bottom plan view thereof.

I claim:

The ornamental design for a storage cabinet, substantially as shown.
